PAVING MACHINE

Charles W. Pierce, La Crescenta, Calif., assignor
to Viber Company, a corporation of California

Application February 14, 1944, Serial No. 522,301

10 Claims. (Cl. 94—45)

This invention relates to paving machines, and in particular to a machine for compacting concrete by internal vibration.

One object of my invention is to provide a machine for the placement of concrete in pavements, slabs and the like which is of large capacity and highly efficient in compacting concrete of large sized aggregates and of low water content. Another object is to provide a machine for leveling, compacting and finishing a concrete slab from a mass of concrete upon a roadway.

Another object is to provide a machine which vibrates the concrete in place on a roadbed.

Another object is to provide a machine which vibrates plastic material such as concrete on a roadbed between crosswise expansion joints, with means for raising and lowering the vibrating mechanism over the crosswise joint members.

Still another object is to provide a mechanism for raising and lowering a gang of vibratory units to avoid crosswise joint members in the roadway.

A further object is to provide means for holding a gang of tubular vibrators in inclined partly submerged operative position while moving the vibrators through the concrete to compact it.

Another object is to provide a paving machine which will place concrete masses which are too harsh and dry to be properly placed on a roadbed by any other known means.

These and other objects will be apparent from the following description and the drawings in which:

Fig. 1 is a plan view showing one form of my paving machine;

Fig. 2 is a side elevation view of the same;

Fig. 3 is a cross-sectional view taken on the line 3—3, the vibrators being omitted for clarity;

Fig. 4 is a cross-sectional view taken on the line 4—4 of Fig. 3;

Fig. 5 is a detail showing the piping connections for the control valves to the hydraulic lines;

Fig. 6 is a perspective view showing the supporting structure for individual vibrator units;

Fig. 7 is an elevation view partly in section showing one of the individual vibrators;

Fig. 8 is a cross-sectional view showing the details of the telescopic arms of the lever mechanism;

Fig. 8a is a top view of the telescopic arm of Fig. 8;

Fig. 9 is a cross-sectional view taken on the line 9—9 of Fig. 8;

Fig. 10 is a cross-sectional view taken on the line 10—10 of Fig. 8;

Fig. 11 is a detail showing the end fastening member of the lever arm of Fig. 8;

Fig. 12 is an enlarged side elevation of the telescopic lever arrangement;

Fig. 13 is an end elevation of the same;

Fig. 14 is a plan view of the same;

Fig. 15 is an enlarged side elevation of an alternative lever arrangement for elevating the vibrators;

Fig. 16 is a front elevation of the same;

Fig. 17 is a plan view of the same;

Fig. 18 is an enlarged side elevation of another alternative lever arrangement for elevating the vibrators;

Fig. 19 is a plan view of the same.

In general, my paving machine consists of a carriage adapted to travel along the strip to be paved, and carrying a power unit, an electrical generator, an hydraulic liquid pressure system, a gang of insertible vibrator units, a cross-the-strip oscillating screed member, and means to insert the vibrators in inclined position to operate beneath the screed member in the concrete, together with means to raise and lower the vibrators to avoid expansion joint members in the paving strip.

My paving or concrete placing machine in its preferred form is shown in Figs. 1 to 14 inclusive, and consists of a carriage having side members 11 and 12 and frame cross members 14, 15, 15', 16, 17, and 18, with flanged wheels 19, 20, 21 and 22 mounted on individual stub shafts in outer bearings 23, 24, 25 and 26 attached to the main frame side members 11 and 12 by brackets 27, 28, 29 and 30; and in rear inner bearings 32 and 33 attached to longitudinal frame members 35 and 36 carried between cross members 16 and 18; and in forward inner bearings 31 and 34 attached to frame cross-members 15' and 16.

The carriage wheels are driven separately on the two sides of the carriage, by hydraulic motors 37 and 38, with suitable sprockets 39 and chains 40 to jack shafts 41 and 42 mounted in outer bearings 43 and 44 attached to side members 11 and 12; and in inner bearings 45 and 46 attached to frame members 35 and 36 between cross members 18 and 16. Sprocket 49 on the jack shaft 41 is arranged to drive the right rear drive sprocket 50 by means of the chain 51; and the sprocket 52 on the jack shaft 41 is arranged to drive the right front sprocket 53 by the chain 54. Likewise on the left side, the sprocket 55 on the jack shaft 42 is arranged to drive the left rear drive sprocket 56 by the chain 57; and the sprocket 58 on the jack shaft 42 drives

the front left drive sprocket 59 by means of the chain 60. The hydraulic valves 61 and 62 at the operator control station provide means for independently operating the motors 37 and 38, to move the flanged drive wheels on either side of the carriage, thus permitting control of the movement of the carriage to attain parallel forward motion. This is important since the temporary tracks for the carriage wheels, usually consisting of the headers 63 of the road strip, are not always in practice accurately placed or levelled. Hydraulic pumps 64 and 65, and liquid reservoir 66, with suitable connecting piping, are provided to actuate the fluid motors 37 and 38 and to connect with the control valves 61 and 62, as shown in Figs. 1, 2 and 5.

Upon the main frame is mounted a gasoline motor 80, whose main shaft is operatively connected to a generator 81 through the coupling 82. The generator supplies electrical energy for operating the motors 67, 68, 70, 71, and 73 actuating the fluid pumps 64, 65, 74, 75 and 76, and for driving the oscillating screed motor 77, and the individual vibrator motors 84 of the vibrating units 69.

My machine is provided with a gang of separate vibratory units 69 of the general type consisting of an elongated tubular housing inclosing a rotary vibratory mechanism attached to a high speed motor, the tubular housing being at least partly insertible in the concrete. While I may use any suitable type of insertible vibrator, I prefer to use one in which a portion of the tubular casing is made semi-rigid or very stiffly flexible. In Fig. 7, the drive shaft 85 of the motor 84 is operatively connected to a vibrator mechanism by means of relatively short length of flexible shafting 86 connected to the vibrator rotor 87, this shafting being enclosed in a semi-rigid housing 88. The vibrator mechanism consists of an eccentric rotor 87 mounted on bearings 90 which are supported by the rigid housing 91. The short length of flexible shafting 86 is encased in a helical coil 93 which in turn is enclosed within a flexible metallic sheathing 94, and this is enclosed within the water-sealing tubing 95 which may be rubber-like composition with suitable metallic or fabric reinforcing to give the desired semi-rigidity and strength. When in the concrete, the tube is rigid enough to maintain itself in substantially straight form but flexible enough so that it may be bent as much as ten to twenty degrees when sufficient force is applied. The advantages of using the semi-rigid tubular vibrator is that it permits the necessary bending either upwardly or laterally to carry the vibrator tubes around obstructions such as manholes and the like, which may be in the roadbed, and thus avoids the necessity of the operator withdrawing the entire gang of vibrators out of the concrete, and insures vibratory action near such obstructions. The semi-rigid tube also gives greater efficiency in the vibratory action because less energy is dissipated to the motor and from the motor to the supports on the machine.

Each of these vibrator units is supported on a movable cross-member 96 by means of a yoke 97 at the end of a leaf spring member 98 which is rigidly attached to the movable cross member 96. The gang of vibrators thus attached to the movable cross member 96 may be so moved by elevator means that the free ends of the vibrator tubes are inserted into the concrete mass, and the tubes then take an operative position inclining downwardly and rearwardly of the machine with the

tubes partly buried in the concrete. As the whole machine moves forward, the vibrator tubes are combed through the mass in this inclined position. The elevator means provides not only for lifting the vibrator tubes out of the concrete by movement parallel to their long axes, but also means are provided to simultaneously move the elongated vibrator tubes from their inclined usual operative position gradually to a vertical position.

5 10 This is desirable when lifting them over the expansion joints in the pavement, and it provides for vibrating the concrete throughout its thickness up to the joint and thus avoiding unvibrated pockets around the expansion joints; and for re-15 inserting them on the forward side of the expansion joints. In order that the free ends of the vibrators in their main operative position be positioned under the oscillating screed member 79, the elevating means also provides for moving the 20 gang forward or backwards relative to the screed.

My preferred elevator means is shown on the machine in Figs. 1 and 2 and in detail in Figs. 8 to 14. Extensible lever members 100 are pivoted on the pin 101 in the clevis 102 attached at a 25 fixed position to the main frame side member 11 or 12 on the inside of the frame at positions intermediate the ends and preferably to the rear of the screed member. Additional elevating means may be provided between the side frame members 30 when the width of the paving machine is such that more than the two shown here are required. The other end of the extensible lever 100 is pivotally fastened to an attachment plate 103 by means of a clevis and piece 104 and pivot pin 105. 35 Attachment plates 103 are welded or otherwise fastened to the vibrator supporting cross-member 96 near its ends.

The lever members 100 are adapted to be varied in length by means of a telescoping tube arrangement hydraulically actuated by pump 74 operable by motor 70 and controlled by a valve 114. An outer tube 106 encloses an inner tube 113 (see Fig. 8) the latter being provided with a plug 107 at its inner end through which a pipe 108 allows fluid to be put in or removed from the fulcrum side of the fixed piston 109; and another pipe 110 is provided through a packing gland 111 in the plug 107 this pipe being attached to and leading through the piston 109, which is provided with sealing rings 112. The pipe 110 is adapted to deliver and return hydraulic liquid to and from the outer end of the tube 113 which is closed by the plug end of the clevis end piece 104. The pipe 110, fixedly secured to the tube 106, holds the piston 109 in fixed position relative to the outer tube 106. When it is desired to lengthen the lever arm 100, hydraulic liquid under pressure under control by valve 114 from the reservoir 66 and pump 74, actuated by motor 70, is forced through pipe 110 into the outer cylinder space causing the tube 113 to move outwardly relative to tube 106. When shortening of the lever arm is required, liquid is forced into pipe 108 causing the tube 113 to telescope inside tube 106 and thus shortening the arm 100.

A short telescoping lever arm 118 is attached to lever member 100 intermediate its ends by means of a clamp member 119 whose ends form a clevis in which one end of the arm 118 is pivoted by the pin 120, this short lever arm being also extensible and similar in construction to lever arm 100. A piston 125 with pressure rings 126 is provided inside an inner telescoping tube 127, its position being fixed relative to the outer tube 128 by the hollow piston rod or pipe 129 which

is attached near the fulcrum end to the outer tube 128 and passes through a packing gland 130 in the inner tube end plug 131, which closes the inner end of tube 127. The hollow piston rod 129 is arranged to discharge pressure fluid into the space beyond the piston 125 in the inner tube 127, whose outer end is closed by the bifurcated end plug 121. The hydraulic liquid is controlled by the valve 124 at the control board, which controls the fluid passing from the reservoir 66 to the pump 76 operable by the motor 73. The outer end 121 of the arm 118 is pivoted by pin 122 to a bracket 123 attached, for example by welding, near the end of the vibrator-supporting cross-member 96 and opposite the attachment plate 103, the pivoting pins 105 and 122 being separated and disposed relative to the supporting cross-member 96 so that the insertible tubes of the vibrator units 69 may be moved angularly from a vertical position to the operative inclined position as described above. The extensibility of the members 100 and 118 not only provides for the turning movement of the cross-member 96 and its attached gang of vibrators, but it also allows positioning the vibrators forwardly and backwardly relative to the oscillating screed member 79.

The extensible lever arm 100 is turned on the fulcrum pin 101 thereby elevating the cross-member 96 and its attached gang of vibrators, by means of an hydraulic lifting jack 133 whose movable piston member 134 is provided with a cap 135 bearing against the lever arm member 100, preferably at the clamp member 119. The lever arm 100 is raised by positive action of the hydraulic jack but the weight of the attached parts permits downward movement against the jack. The jack 133 on either side is supported below the side members 11 or 12 by means of a bracket 135, and hydraulic liquid lines 136 and 137 from the pump 75 through the control valve 117 at the control station furnish the actuating pressure liquid. By manual manipulation of the valves controlling the lengthening and shortening of the lever arms 100 and 118, and the lifting jack 133, the positions of the vibrators 69 and their insertible tube portions may be controlled at the beginning and ending of a paving strip, and in the operative position during passage through the length of the strip, at positions immediately below the oscillating cross-screed member 79. The several positions of the elevating and turning means and the vibrators are shown in Figs. 2 and 12.

Alternative arrangements for elevating and turning the vibrators mounted in a gang on the supporting cross-member 96 are shown in Figs. 15 to 19. Referring to Figs. 15, 16 and 17, which show the first of these alternative arrangements as applied to the right side of the carriage (it being clear that a duplicate arrangement of the left side of the carriage, and intermediate the sides if desired, may be provided), a long lever arm 165 is pivoted by pin 166 in the clevis bracket 167 mounted on the side member 11 of the carriage, the other end of the lever being pivotally attached to the hinge pin 168, this pin serving also as a fulcrum for the short lever arm 169. The short lever arm 169 has a short portion extending beyond the fulcrum at 168, which is rigidly attached to the end of the vibrator supporting cross member 96; the other end of the lever arm 169 is pivotally attached to the piston rod 170 of the reversible hydraulic jack 171,

which has its base pivotally attached to the carriage side member by a bracket 172, its point of attachment being forward from the fulcrum of the main lever arm 165. A second hydraulic jack 173 is also mounted on the bracket 174 attached to the side member 11, this jack being pivotally fastened to the long lever arm 165 intermediate its ends, by means of a pivoted link 175. Suitable hydraulic pipe lines for actuating the jacks 171 and 173 are provided, with suitable valves at the control panel for manual operation by the operator. The jack 173 functions to lift the gang of vibrators vertically, and the short lever arm 169 with the jack 171 effects the turning of the vibrator assembly around the axis of the hinge pin 168. The several positions taken by the insertible end of the vibrators and the pivot centers are shown in Fig. 15, it being possible to position the vibrator in inclined operating position beneath the screed member 79, and on occasion to bring it to a vertical position and lift it out of the concrete, as over a separator strip, and back again, by suitable manipulation of the two jacks 171 and 173.

25 A second alternative elevating and turning arrangement is shown in Figs. 18 and 19. A long lever arm 180 is pivoted by the pin 181 on the bracket 182 mounted on the side member 11, its other end being pivoted by the hinge pin 183 to the piston 183 of the hydraulic jack 184, mounted on the side member 11 by bracket 185. Intermediate the fulcrum 181 and the hinge pin 186, is mounted the main jack 187 on the side member 11, the extensible piston rod of the jack being fastened to the movable bracket 188, the lower end of which forms a seat for a third hydraulic jack 189, arranged so that jack 187 will raise and lower the third jack 189. The third jack 189 is provided with a pivoted link member 190 which is pivotally attached at 192 also to the short lever arm 191 which is pivoted near its center on the hinge pin 186. The outer end of the lever arm 191 is rigidly fastened to the end of the vibrator supporting cross-member 96. Hydraulic lines, with control valves at the operator's station, are provided to the three jacks, and by suitable operation of the jacks, the vibrators may be made to take the various positions, as shown in Fig. 18, from the inclined operative position in the concrete beneath the screed member 79 to the vertical position in and out of the concrete, as shown, thus permitting the vibrating of the concrete up to a dividing line such as an expansion joint member, with vertical reinsertion of the vibrator tube followed by positioning in the inclined operative position under the screed. The use of the two jacks 187 and 189 instead of one long jack gives better operating control by limiting the movement in two steps limited by the length of lift of each jack.

60 Referring particularly to Figs. 1, 3 and 4, the cross screed member consists of a screed plate 140 which is attached to the forward side of a screed frame 141 which extends across the roadway and is provided with shoes 142 which slide on the top edge of the header or side boards 63. The vertical position of the screed plate is adjustable by hand wheels 143 at either end, and contour plates 144 adjustably attached to the screed plate act to shape the concrete at the edge of the road or strip. Wings 145 are provided to push any spreading concrete back onto the roadbed. The screed frame is supported from the cross member 15 of the main frame by bell

cranks 146 which are supported by brackets 147 rigidly attached to the member 15. The forward end of each crank is provided with a roller 148 which supports the screed frame 141 under the channel iron brackets 149 on the frame, this allowing horizontal movement of the screed frame corresponding to its oscillatory movement across the strip. The free end of each bell crank is connected by a cable to the control wheel 150 so that the operator may adjust the level of the screed as required during operation. The forward and backward thrust of the screed 140 and the screed frame 141 at any position in their oscillating movement is taken by the vertical rollers 151 which are mounted on brackets 152 attached to the cross member 15, each rolling between three horizontal rolls 153, 154 and 155 attached to the screed frame 141.

The oscillatory movement of the screed is provided by an arm 157 attached near the middle of the screed frame and driven by the motor 77 with its speed-reducing unit 159, a crank 160 being provided on its shaft 161.

In operating my machine along a strip which has been prepared for a concrete slab, including the insertion of the cross expansion-joint members, the machine is moved slowly over the area upon which unset concrete has been roughly distributed. The vibrators are lowered into the concrete by means of the elevator mechanism as described and are "combed" through the levelled-off concrete in an inclined position with the maximum amount of vibration being delivered in the concrete beneath the screed. As the machine is advanced, the concrete is distributed, compacted and levelled off to the desired grade by the combined action of the vibrators and the oscillating screed member placed directly above the operative inserted ends of the vibrators. Any entrapped air, and excess water follows up the vibrator tubes and the concrete mass becomes consolidated and no perceptible furrow is left by the vibrators because these are continuously closed behind the tubes. By means of my paving machine, much drier and harsher mixes of concrete may be properly placed on a roadway than has been possible by presently available methods. The surface may be further finished if desired by suitable means following the vibrators and screed.

While I have illustrated my invention by a preferred embodiment, I do not wish to be restricted to the particular arrangement shown, but limit my invention only insofar as required by the prior art and the spirit of the appended claims.

I claim:

1. In a machine for compacting concrete on a roadway, the combination with a carriage frame of vibrator elevator means comprising a movable support member disposed crosswise of the machine adapted to hold as a gang a plurality of individually actuated elongated vibrator units, main lever means attached at fulcrums to the carriage frame for raising and lowering said support member including complete withdrawal of said units from the concrete space on the roadway, hydraulic jacks for moving said main lever means, and means to turn said support member during operation to position and hold the elongated attached vibrator units in any selected rearwardly downwardly inclined position from the vertical; and a gang of tubular vibratory units held by said movable support member, each vibratory unit having an elongated casing part adapted for partial insertion in the unset concrete on the roadway and each unit having

independent actuating means attached to the non-insertible portion of said casing part.

2. In a machine for compacting concrete on a roadway, the combination with a carriage frame of vibrator elevator means comprising a movable support member disposed crosswise of the machine adapted to hold as a gang a plurality of individually actuated elongated vibrator units, main lever means attached at fulcrums to the carriage frame for raising and lowering said support member including complete withdrawal of said units from the concrete on the roadway, hydraulic jacks for moving said main lever means, and means to turn said support member during operation to position and hold the elongated attached vibrator units in any selected rearwardly downwardly inclined position from the vertical in front of or beneath a screed member; a gang of tubular vibratory units held by said movable support member, each vibratory unit having an elongated casing part adapted for partial insertion in the unset concrete on the roadway and each unit having independent actuating means attached to the non-insertible portion of said casing part, and an oscillating screed member supported by the carriage frame at the road surface and in normal operative position directly over said inclined vibrator parts submerged in the concrete therebeneath.

3. In a machine for compacting concrete on a roadway, the combination with a carriage frame of vibrator elevator means comprising a movable support member disposed crosswise of the machine adapted to hold as a gang a plurality of individually actuated vibrator units each having an elongated vibratory casing part adapted for partial insertion in the concrete to deliver vibrations thereto, brackets attached to said support member for pivotal attachment of lever arms thereto, extensible main lever arms attached at fulcrums to the frame of said carriage and pivoted at the other end to said support member for raising and lowering said support member, means for varying the lengths of said main lever arms, hydraulic jacks for moving said main lever arms, extensible turning arms attached at fulcrums to said main lever arms intermediate the ends thereof and pivoted at their other ends to said brackets on said support member, means for varying the lengths of said turning arms, said extensible arms, length varying means and brackets being arranged and adapted to position and hold the elongated vibrator casing parts in any selected rearwardly downwardly inclined position from the vertical; and a gang of tubular vibratory units held by said movable support member, each vibratory unit having an elongated casing part adapted for partial insertion in the unset concrete on the roadway and each unit having independent actuating means attached to the non-insertible portion of said casing part.

4. In a machine for compacting concrete on a roadway, the combination with a carriage frame of vibrator elevator means comprising a movable support member disposed crosswise of the machine adapted to hold as a gang a plurality of individually actuated vibrator units each having an elongated vibratory casing part adapted for partial insertion in the concrete to deliver vibrations thereto, brackets attached to said support member for pivotal attachment of lever arms thereto, extensible main lever arms attached at fulcrums to the frame of said carriage and pivoted at the other end to said support

member for raising and lowering said support member, means for varying the lengths of said main lever arms, hydraulic jacks for moving said main lever arms, extensible turning arms attached at fulcrums to said main lever arms intermediate the ends thereof and pivoted at their other ends to said brackets on said support member, means for varying the lengths of said turning arms, said extensible arms, length varying means and brackets being arranged and adapted to position and hold the elongated vibrator casing parts in any selected rearwardly downwardly inclined position from the vertical in front of or beneath a screed member; a gang of tubular vibratory units held by said movable support member, each vibratory unit having an elongated casing part adapted for partial insertion in the unset concrete on the roadway and each unit having an independent actuating means attached to the non-insertible portion of said casing part and an oscillatory screed member disposed at the road surface supported by said carriage frame in normal operative position directly over said inclined vibrator casing parts submerged in the concrete therebeneath.

5. In a machine for compacting concrete on a roadway, the combination with a carriage frame of vibrator elevator means comprising a movable support member disposed crosswise of the machine adapted to hold as a gang a plurality of individually actuated vibrator units each having an elongated vibratory casing part adapted for insertion in the concrete to deliver vibrations thereto, brackets attached to said support member for pivotal attachment of lever arms thereto, telescoping tubular main lever arms attached at fulcrums to the frame of said carriage and pivoted at the other ends to said support member for raising and lowering said support member, means including a fixed piston inside the closed movable inner tube and pipe lines for conducting pressure liquid to and from either side of said piston for varying the lengths of said main lever arms, hydraulic jacks for moving said main lever arms, telescoping tubular turning arms attached at fulcrums to said main lever arms intermediate the ends thereof and pivoted at their other ends to said brackets on said support member, and means for varying the lengths of said turning arms including a fixed piston inside a closed movable inner tube with pipelines for conducting pressure liquid to and from either side of said piston, said levers, turning arms, and length varying means and the brackets being arranged and adapted to position and hold the elongated vibrator casing parts in any selected rearwardly downwardly inclined position from the vertical.

6. In a machine for compacting concrete on a roadway, the combination with a carriage of the vibrator elevator and turning means of claim 5, and an oscillatory screed member disposed at the road surface supported by said carriage frame, and in normal operative position being directly over said inclined elongated vibrator casing parts submerged in the concrete therebeneath.

65

7. In a machine for compacting concrete on a roadway, the combination with a carriage frame of vibrator elevator means comprising a movable support member disposed crosswise of the machine adapted to hold as a gang a plurality of individually actuated vibrator units each having an elongated vibrator casing part adapted for insertion in the concrete to deliver vibrations thereto, main lever arms attached at fulcrums to the frame of said carriage for raising and lowering said support member, main hydraulic jacks for raising and lowering said main lever means, and turning levers for said support member pivoted intermediate the ends thereof to the ends of the main lever arms, the outer ends of said turning levers being attached to said support member and the other end being pivotally attached to a second hydraulic jack, adapted to position and hold the elongated vibrator casing parts in any selected rearwardly downwardly inclined position from the vertical.
8. In a machine for compacting concrete on a roadway, the combination with a carriage frame of the vibrator elevating and turning means of claim 7, and an oscillatory screed member disposed at the road surface supported by said carriage frame, and in normal operative position directly over said elongated vibrator casing parts submerged in the concrete therebeneath.
9. In a machine for compacting concrete on a roadway, the combination with a carriage frame of vibrator elevator means comprising a movable support member disposed crosswise of the machine adapted to hold as a gang a plurality of individually actuated vibrator units each having an elongated vibrator casing part adapted for insertion in the concrete to deliver vibrations thereto, main lever arms attached at fulcrums to the frame of said carriage for raising and lowering the said support member, main hydraulic jacks for raising and lowering said main lever means, turning levers for said support member pivoted intermediate the ends thereof to the ends of the main lever arms, the outer ends of said turning levers being attached to said support member and the other end being pivotally attached to a secondary hydraulic jack, secondary hydraulic jacks pivotally connected to said turning levers, and elevating hydraulic jacks attached to the carriage frame adapted to raise and lower the position of said secondary jacks relative to said main frame, said levers and jacks being arranged and adapted to position and hold the elongated vibrator casing parts in any selected rearwardly downwardly inclined from the vertical position.
10. In a machine for compacting concrete on a roadway, the combination with a carriage of the vibrator elevator and turning means of claim 9, and an oscillatory screed member disposed at the road surface supported by the carriage frame, and in normal operative position directly over said elongated vibrator casing parts submerged in the concrete therebeneath.

CHARLES W. PIERCE.
